(57) **CLAIM**

The ornamental design for a toe protector, as shown and described.

DESCRIPTION

FIG. 1 is a perspective view of a toe protector, showing my new design;

FIG. 2 is a perspective view thereof;

FIG. 3 is a front view thereof;

FIG. 4 is top view thereof;

FIG. 5 is a bottom view thereof; and,

FIG. 6 is a left side view thereof, the right side view being identical to the left side view shown.

The broken line showing is for illustrative purposes only and forms no part of the claimed design.
